PASTE WAX APPLICATOR

Drury H. Charles, Phelps, Ky.

Application August 13, 1952, Serial No. 304,145

2 Claims. (Cl. 15—131)

This invention relates to devices for applying wax to floors and the like, and in particular a box like casing having a pressure plate or follower therein with means for actuating the follower by foot pressure whereby the follower forces wax through opening in a base for applying the wax and in which the base is provided with a moistening cover for retaining the wax in a moist condition when the device is not in use and which is also adapted for use in rubbing and polishing the waxed floor.

The purpose of this invention is to provide means for applying wax in paste form to floors whereby the operator may remain in an upright position.

Because of the inconvenience of applying wax to floors with cloths and other devices wax is applied in liquid form however, as the liquid wax does not have the body of the conventional paste wax the wax in paste form is preferred. With this thought in mind this invention contemplates a wax applying device in which wax is forced through openings in the base of a housing or casing by a screw actuated pressure plate or follower whereby the wax may be applied with the operator in an upright position.

The object of this invention is, therefore, to provide means for forming an applicator for waxing floors whereby wax, in paste form is readily forced from the device as it is used.

Another object of the invention is to provide a device for applying wax in paste form to floors and the like in which the same device may be used for polishing the floor.

A further object of the invention is to provide a device for applying wax in paste form to floors in which the operator remains in an upright position, in which the device is of a simple and economical construction.

With these and other objects and advantages in view the invention embodies a box like casing having a sliding cover with a felt pad on the under surface and having a follower mounted on a screw extended through the casing whereby wax in paste form in the casing may be forced through openings in the bottom of the casing and also through a slot in a pad or felt or the like on the under surface of the casing.

Other features and advantages of the invention will appear from the following description taken in connection with the drawing, wherein:

Figure 1 is a view illustrating the general design and appearance of the improved paste wax applicator.

Figure 2 is a cross section through the device taken on line 2—2 of Fig. 1.

Figure 3 is a detail showing a panel positioned on the lower end of the casing and providing the bottom thereof.

Figure 4 is a detail illustrating a pad of felt or the like that is positioned against the under surface of the casing.

Figure 5 is a similar detail showing a moistening and polishing panel of felt or the like that is positioned over the lower end or bottom of the casing.

Referring now to the drawing wherein like reference characters denote corresponding parts the improved paste

2

wax applicator of this invention includes a casing having a rear wall 10, a front wall 11, end walls 12, a cover 13 and a panel 14 which provides a bottom, and the casing is provided with a follower 15 on which is a nut 16 through which a screw 17 having a wing nut 18 on the outer end extends.

These elements provide a box like casing and the panel 14 providing the bottom is provided with a row of openings 19 through which wax is forced by the follower 15. The panel 14 is also provided with openings 20 for screws 21 and, as shown in Figs. 2 and 3 the panel is provided with a continuous flange 22 that overlaps the edge of the casing.

A pad 23 which is formed of felt or the like and which is provided with a slot 24 is secured to the under surface of the panel 14 and the slot 24 is in registering relation with the openings 19.

The device is also provided with a moistening layer or panel 25 that is provided with flanges 26 at the edges and lips 27 on the upper edges of the flanges extend over the projecting flange 22 of the panel 14, as shown in Fig. 2.

As illustrated in Fig. 1 the cover 13 is provided with ribs 28 and 29 that extend into slots 30 and 31, respectively in the end walls 12 of the casing and, by means of a recess 32 the cover may be withdrawn to facilitate refilling the casing with wax. The rear edge of the cover 13 is also provided with a rib 33 that extends into a slot 34 in the rear wall 10.

The cover is retained in the closed position with pivotally mounted latches 35 and 36, which are mounted on the front wall 11 with pins 37 and 38, respectively and the upper ends of the latches are positioned to contact with clips 39 and 40.

The casing is provided with a handle 41, one end of which is inserted into a socket 42 on a yoke 43, the ends of which are pivotally mounted on the end walls of the casing with pins 44. It will be understood that a handle of any suitable type or design may be provided and the handle may be mounted on the casing by suitable means.

The screw 17 is journaled in the front wall 11 with a bushing 45 and rear wall 10 with a bushing 46. The wing nut 18 is fixedly mounted on the outer end of the screw and, as shown in Fig. 2, the screw is provided with spacing washers 47 and 48 that are positioned against inner and outer surfaces of the front wall 11.

The opposite end of the screw is provided with a head 49 that is positioned to bear against a threaded section 50 of a flange 51 which is secured to the rear wall 10 with screws 52. A cap 53 is threaded on the section 50 of the flange 51 providing a cover for the head 49 of the screw.

With the parts arranged in this manner floor wax in paste form is placed in the box like casing with the follower 15 and backing member 54 thereof positioned adjacent the inner surface of the front wall 11 and with the member 25 removed the wax is forced through the perforations 19 and slot 24 to the floor, the adjoining sections of the panel 23 being saturated with wax whereby the wax may readily be rubbed on a floor with the device operated by the handle 41.

After rubbing the wax on the floor the members 25 may be placed over the lower end of the applicator 65 whereby the device is adapted to be used for polishing the floor. The member 25 also provides means for enclosing the applying panel 23 whereby wax around the slot 24 is maintained in a comparatively soft condition.

As the device is used the screw 17 is rotated by turning the nut 18 with the foot of the operator whereby the follower 15 is continuously moved to force wax from the casing as the wax is used.

It will be understood that modifications, within the scope of the appended claims, may be made in the design and arrangement of the parts without departing from the spirit of the invention.

What is claimed is:

1. In an applicator for wax in paste form, the combination which comprises a box like casing having a bottom panel having a row of openings spaced from one edge thereof with rear, front, and end walls extended upwardly from the bottom panel and a cover slidably mounted in the end walls, a fibrous panel positioned against the lower surface of the bottom panel of the casing and having a slot positioned to register with the openings through the bottom panel, a vertically disposed follower positioned in the casing and a transversely disposed screw extended through the follower and journaled in the front and rear walls of the casing, said screw having a wing nut fixed on the end extended through the front wall thereof whereby upon the turning of said wing nut said screw will be caused to rotate thereby moving the follower, and a handle pivotally mounted on the casing and extended therefrom.

2. In an applicator for wax in paste form, the combination which comprises a box like casing having a bottom panel having a row of openings spaced from one 25

edge thereof with rear, front, and end walls extended upwardly from the bottom panel and a cover slidably mounted in the end walls, a fibrous panel positioned against the lower surface of the bottom panel of the casing and having a slot positioned to register with the openings through the bottom panel, a vertically disposed follower positioned in the casing and a transversely disposed screw extended through the follower and journaled in the front and rear walls of the casing, said screw having a wing nut fixed on the end extended through the front wall thereof whereby upon the turning of said wing nut said screw will be caused to rotate thereby moving the follower, a handle pivotally mounted on the casing and extended therefrom, and a covering panel also of fibrous material and having flanges at the edges for retaining the panel in position on the bottom of the casing and for retaining wax in the slot in a moist condition.
